UNITED STATES PATENT OFFICE.

CHARLES M. HUNTINGTON, OF EAST RANDOLPH, NEW YORK, ASSIGNOR OF ONE-THIRD TO JAY WALKER AND ONE-THIRD TO CLYDE JOHNSON, BOTH OF EAST RANDOLPH, NEW YORK.

REVOLVING SIGN.

Application filed January 19, 1924. Serial No. 687,266.

To all whom it may concern:

Be it known that I, CHARLES M. HUNTINGTON, a citizen of the United States, residing at East Randolph, in the county of 5 Cattaraugus and State of New York, have invented a new and useful Revolving Sign, of which the following is a specification.

This invention relates to signs to be used for advertising purposes, the primary object of the invention being to provide a revolving sign wherein a plurality of advertisements may be viewed at all times.

Another important object of the invention is to provide a device of this character embodying a plurality of signs, novel means being provided for revolving the signs in opposite directions to attract attention.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawing:

Figure 1 is an elevational view disclosing a sign constructed in accordance with the invention and illustrating the upper end of its supporting post.

Figure 2 is a longitudinal sectional view through the upper portion of the post.

Figure 3 is an end elevational view of a modified form of sign.

Figure 4 is an end elevational view of a further modified form of the sign.

Referring to the drawing in detail, the 40 reference character 5 designates a supporting post which may be of any desired construction, to the upper end of which is secured a hollow section 6, which provides a bearing for the vertical shaft 7.

Mounted on the upper end of the section 45 6 is a supporting member 8 which is formed with a hollow section 9 fitted over the upper end of the section 6 in a manner to permit the member 8 to revolve around the section 6 for purposes to be hereinafter more fully described.

The supporting member 8 also includes 50 upwardly extending bearing members 10 in which the shaft 11 operates, collars 12 being provided on the shaft 11 and disposed ad-

jacent to one of the members 10 to hold the shaft 11 against movement longitudinally within the bearings.

Secured to the shaft 11 and disposed at the outer end thereof, is a wind wheel 13 which operates to rotate the shaft 11. Secured to the shaft 11 is a beveled pinion 14 that meshes with the beveled pinion 15 secured to the upper end of the shaft 7 so that rotary movement of the pinion 14 is transmitted to the shaft 7 to rotate the worm 16 secured to the lower end thereof.

As shown, the section 6 is formed with lateral cut out portions providing clearances for the pinions 17 that are carried on the inner ends of the shafts 18 operating in the bearings 19 forming a part of the section 6.

These shafts 18 provide supports for the signs 20, each of which signs being in the form of a frame covered by a flexible material 21, which flexible material may be printed or otherwise supplied with suitable indicating characters or reading matter setting forth some form of advertisement.

In order that the windwheel 13 will be held into the wind at all times, the usual blade 22 is provided, so that the position of the windwheel will be changed with the changing of the direction of the wind.

Secured to the post 5 are arms 23 that are provided with upwardly extended end portions 24 supplied with bearings 25 to receive the outer ends of the shafts 18 and support the same.

As shown by Figure 3 the frame of the sign is indicated at 26 to which frame is secured a covering 27 that may be supplied with suitable indicating characters. As shown by Figure 4, the sign proper is substantially triangular in formation and includes a frame 28 covered by the member 29 that may carry the indicating characters that constitute the sign.

From the foregoing it will be obvious that due to this construction, the windwheel 13 will operate to rotate shaft 11 which in turn transmits motion to the shaft 7 through the pinions 14 and 15 the shaft 7 operating to rotate the signs as before stated, which are supplied with suitable indicating characters.

I claim:

A revolving sign including a supporting post, a hollow section positioned within the

supporting post, said hollow section having cut out portions formed intermediate its ends, a vertical shaft in the hollow section, a worm on the vertical shaft, said worm having portions thereof disposed within the cut out portions, laterally extending supporting arms secured to the supporting post, horizontal shafts supported by the arms, said shafts carrying pinions on their inner ends, said pinions adapted to mesh with the worm of the vertical shaft to receive motion therefrom, a beveled pinion at the upper end of the vertical shaft, a wind wheel mounted

at the upper end of the hollow section, means for transmitting movement of the wind wheel to the beveled pinion to rotate the vertical shaft to rotate the signs carried thereby.

In testimony that I claim the foregoing as my own, I have hereto affixed my signature in the presence of two witnesses.

C. M. HUNTINGTON.

Witnesses:

JAY L. WALKER,
FLORENCE HOVEY.
